(57) **CLAIM**

The ornament design for a seal plate for rotary machine, as shown and described.

DESCRIPTION

FIG. 1 is a front view of a seal plate for rotary machine according to a first embodiment of our new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof.

FIG. 8 is a cross-section view taken along line 8-8 in FIG. 1.

FIG. 9 is a cross-section view taken along line 9-9 in FIG. 1.

FIG. 10 is a front view of a seal plate for rotary machine according to a second embodiment of our new design.

FIG. 11 is a rear view thereof.

FIG. 12 is a left side view thereof.

FIG. 13 is a right side view thereof.

FIG. 14 is a top view thereof.

FIG. 15 is a bottom view thereof; and,

FIG. 16 is a perspective view thereof.

1 Claim, 16 Drawing Sheets
